UNITED STATES PATENT OFFICE.

HENRY W. BRECKENRIDGE, OF PROVIDENCE, RHODE ISLAND.

SWITCH FOR TELEPHONE-EXCHANGES.

SPECIFICATION forming part of Letters Patent No. 252,421, dated January 17, 1882.

Application filed July 22, 1881. (No model.)

To all whom it may concern:
Be it known that I, HENRY W. BRECKENRIDGE, of the city and county of Providence, State of Rhode Island, have invented a new and useful Improvement in Switches for Telephone-Exchanges; and I hereby declare that the following is a full, clear, and exact description of the same, reference being had to the accompanying drawings, forming part of this specification.

This invention relates to a switching apparatus for including the operator's telephone in or removing it from any of a number of subscribers' lines terminating at the central office of a telephone-exchange, its object being to enable the circuit connection and disconnection of the telephone with and from the several lines to be effected without interrupting the continuity of said lines, and to facilitate the connection of different subscribers' lines with each other.

The invention is designed for supplementary use in connection with any number of line-connecting switch-boards, which may be of any ordinary or suitable construction, and it may be regarded as a modification of the listening-operator system, relieving the listening operator of the close application of keeping his ear always to his telephone, and enabling him to receive a signal or call by means of any suitable devices, and then ascertain the subscriber's wants and communicate the same to the various line-connecting switch-board operators in order that the desired connections may be made.

In the accompanying drawings, Figure 1 is a transverse section of the telephone supplementary switch-board illustrated in Fig. 3, the circuit-connections and switch devices being shown in full lines with the operator's telephone included in a subscriber's line. Fig. 2 is a similar view with the telephone cut out and the line-circuit completed through the switch. Fig. 3 is a front view of a portion of a telephone switch-board according to my invention provided with a series of switches, each arranged to include the operator's telephone in or disconnect it from a subscriber's line.

The letter A designates the board or base

which supports the switches, and B a series of metallic posts, each of which has a portion of its length inserted in an aperture in the board, and its inner end provided with a binding-screw and washers in the ordinary manner, as shown at b. A portion of each post projects in front of the board, and is bifurcated to receive the metallic base c of a jack, C, which is pivoted thereto, and is provided with two curved arms, d and d', projecting in opposite directions, so that they may be swung into contact respectively with metallic spring-arms D and D', which project from the face of the board on opposite sides of the jack, each being connected with a separate metallic bolt, as at f and f', extending through the board and provided with a binding-nut and washer for securing a wire in the usual manner, as at f'. The board may be provided with any convenient number of jacks and contact-springs, and in practice may be arranged for connection with each of the subscribers' lines terminating at the several line-connecting switch-boards in a central office.

Each of the contact-springs D' is provided with an outwardly-curved extension, d'', which hooks over a metallic rod, E, which is supported in front of the board by suitable standards, e, in such position that when the springs D' are left free the inner surfaces of these extensions d'' will bear against said rod.

A wire, F, (shown in Fig. 3,) connects all the posts f at the back of the board, and leads to one of the binding-posts of the telephone T, from the other binding-post of which a wire, F', leads to the rod E.

The subscribers' lines L, entering the central office, are respectively connected to the posts B, which support the jacks C, and from each bolt f', which is connected with a spring, D', a wire, L', leads to a line-connecting switch-board. If one hundred and fifty lines enter the central office they might all be connected with the jacks, as described, of a single telephone switch-board, and their continuations—that is, the wires L'—might be connected by groups of fifty each with three different line-connecting switch-boards, so that one telephone-operator could receive the calls and give the necessary directions to all the connecting

switch-operators, and even to a greater number than I have mentioned simply for illustration.

The operation of the invention is as follows: 5 The jacks C of the telephone switch-board are all nominally turned to the position shown in Fig. 2, so that the arms d' strike the springs D', forcing said arms outwardly, so that their extensions d'' are carried out of contact with the rod E. The line-circuit is thus completed, as indicated by the arrows No. 1 in Fig. 2—that is, from the entering-line L over post B, the arm d' of jack C, spring D', post f', and wire L' to the line-connecting switch-board, 15 which is not shown in the drawings, as any suitable apparatus for the purpose may be used—and the wires L' connected therewith as line-terminals usually are. The telephone, it will be observed, is not in the line-circuit when 20 the jack is in this position. If now a call is received by means of an electric bell or an annunciator connected with a subscriber's line in the usual manner and in sight or hearing of the telephone-switch operator, he turns the 25 jack C of that particular subscriber's line on its pivot to the position shown in Fig. 1, so that the arm d will come in contact with spring D, thus including his telephone in the line in order that he may communicate with the calling 30 subscriber and ascertain his wants, the circuit being now formed, as indicated by the arrows No. 2, from the line L over post B, the arm d of jack C, spring D, bolt f, wire F to one binding-post of the telephone T, and from the other 35 binding-post over wire F' to rod E, thence over the spring D' and its extension d'', and the bolt f' to wire L', and on to the line-connecting switch-board. The arms d and d' of the 40 jack C are of such length and shape that as the jack turns toward spring D' the extension d'' of the spring D' will be permitted to come in contact with the rod E, and the arm d will strike spring D before the arm d' leaves the spring D', so that the new route for the 45 electric current is established from line L to wire L' through the telephone before the old one is broken, and thus is avoided any disturbance to parties using the line when the operator connects or disconnects his or her 50 telephone. Having his telephone now in the line-circuit, the operator ascertains the wants of the calling subscriber. If he desires to communicate with a subscriber on some other line, the telephone-operator repeats back the oral 55 call in a tone loud enough to be heard by the proper line-connecting switch-board operator, who proceeds to make the desired connection, and if the line to be connected with terminates at some other board than his own, he 60 ranges his switching devices and gives notice to the operator at the other switch-board accordingly.

The telephone-operator may keep his telephone in circuit long enough to see that the proper connections have been made, and then 65 remove it without interrupting the communication, as the electrical connection between line L and wire L' is never broken, as has been shown; or he may interpose his telephone at any time by means of the switch of either of 70 two lines in communication without interrupting the communication.

What I claim is—

1. A supplementary telephone-switch comprising a series of swinging jacks or levers of 75 conducting material adapted for connection with separate subscribers' circuits, a metallic spring contact on each of two opposite sides of each of said jacks, a common conductor with which all the spring-contacts on one side of the 80 series of jacks make electrical connection when their respective jacks are in connection with the opposite contacts, but from which conductor they are separated when they are themselves in electrical connection with the jacks, the construction of the jacks being such that they make connection with the contacts toward which they are moved before breaking connection with those from which they are moved, substantially as described. 90

2. The telephone-switch herein described, consisting of the swinging jack C, arranged for connection to the subscriber's line, and provided with the arms d and d', the springs D and D', arranged for connection respectively with a telephone and a switch-board, and the rod E, arranged to be put in or out of connection with spring D' by the action of the jack, and to be connected also with the telephone, substantially as described. 95

3. The combination of the jack C, provided with the arms d and d', the springs D and D', and rod E, the said spring D' being arranged to be driven out of and brought into connection with the rod by the action of the 105 jack, but to be in connection with said rod and jack during a portion of the movement of the jack in contact with the other spring, substantially as and for the purpose set forth. 100

4. The supplementary telephone switch-board provided with a series of jacks, the two series of springs arranged for alternate connection with said jacks, and the rod E, substantially as described, one series of springs being electrically connected with each other and the others arranged for individual or separate connection with and disconnection from the rod by the action of the jacks, substantially as and for the purpose set forth. 110 115

HENRY W. BRECKENRIDGE.
